ROLLING SCREEN

Julian J. Woloszyn, Johnson City, N. Y.

Application June 22, 1936, Serial No. 86,444

2 Claims. (Cl. 156—39)

This invention relates to screens as used in preventing insects from entering a building when the windows are raised.

An object of the invention is to provide a screen 5 detachably engaged with the window sash in such manner as to be raised and lowered with it.

A further feature is in the provision of run ways for the side edges of the screen, attached to the window frame, preventing the passage of insects 10 and also maintaining the screen in operative position irrespective of air currents.

Another purpose is to produce a screen which is automatically coiled upon a roller with the descent of the sash and which maintains the 15 screen at all times under tension.

These and other like objects are accomplished by the novel construction and combination of parts hereinafter described and shown in the annexed drawings, forming a material part of this 20 disclosure, and in which:—

Figure 1 is a front elevational view of a conventional type of dwelling house window showing an application of the invention.

Figure 2 is a longitudinal sectional view taken 25 on line 2—2 of Figure 1.

Figure 3 is a similar sectional view taken on line 3—3 of Figure 1.

Figure 4 is a transverse sectional view taken on line 4—4 of Figure 1, drawn to an enlarged scale.

Figure 5 is a partial side elevational, partial sectional view, the section being taken on line 5—5 30 of Figure 7.

Figure 6 is a sectional view taken on line 6—6 of Figure 5.

Figure 7 is a transverse sectional view taken on line 7—7 of Figure 5.

Figure 8 is a similar sectional view taken on line 8—8 of Figure 5.

Figure 9 is a longitudinal sectional view taken 40 through the spring actuated roll on which the screen is coiled.

Figure 10 is a front elevational view of a window, similar to Figure 1, but showing the screen at the top of the window.

45 A conventional window frame is designated generally by the numeral 15 carrying upper and lower sashes 16—17 respectively.

Mounted on the sill or lower element of the 50 window frame is a box-like casing 18 flush with the front of the frame 15.

Disposed over the end portions of the permanent cover of the casing are plates 20 having slots 21 to receive screws 22 and raised vertically from 55 these plates are uprights 23 forming the outer

walls of narrow chambers 24 having rear walls 25 and closed at their outer edges as shown.

Movable in these chambers are the narrow ends 26 of a cross bar 27 while at their opposite, outer ends are blocks 28.

Fixed on the bar 27 are clips 30 adapted to engage the lower members of the inner sash, while their inner portions 31 extend conveniently to be grasped by the hand in raising or lowering the sash.

Secured in the underside of the bar 27 is the upper edge of a woven wire screen 32. The lower edge of the screen is attached to a roll 33 rotatably mounted in the casing 18, and as will be noted the side edges of the screen enter the chambers 15 24 through narrow passages in their adjacent sides.

Attached to the blocks 28 are chains 35' reaching downwardly and coiled around the ends of the roll 33 in such manner that the bar 27 is held in constant tension irrespective of the screen 32, as the roll 33 has mounted in it a spindle 34 actuated by a coiled spring 35 and tensioned by an extending lug 36, the device being in fact a modification of the well known curtain roll.

As shown in Figure 10, the screen device may be applied at the top of the window, as well as at the bottom, and it will be understood that the screen roll structure when once applied can remain in position indefinitely and obviously is 30 raised and lowered with the sash.

Although the improvements have been described with considerable detail and with respect to certain particular forms of the invention, it is not desired to be limited to such details since 35 many changes and modifications may well be made without departing from the spirit and scope of the invention in its broadest aspect.

Having thus described the invention, what is claimed as new and desired to secure by Letters 40 Patent, is:—

1. In a screen for windows having slideable sashes, a casing fixed on the sill of said window, chambered uprights communicating with said casing at its ends, a cross bar extending between said uprights and movable therein said bar having guide blocks at its ends, clips on said bar adapted to engage one of said sashes, a spring actuated roll revolvable in said casing, a screen having its side edges slideable within said uprights, 45 said screen being fixed at its upper end to said bar and at its lower end to said roll, and flexible connections between said blocks and said roll to relieve the screen from tension.
2. In a screen for windows having slideable 50

55 60 65 70 75 80 85 90 95 100

sashes, a casing extending across said window, a spring actuated roll mounted to rotate in said casing, chambered uprights on said casing extending contiguous to the window frame, a bar having blocks at its lateral ends movable in said uprights, a screen having its edges extending into said uprights, said screen being fixed at its upper edge

5 to said bar and adapted to coil about said roll at its lower edge, chains engaged with said blocks and coiled on said roll to relieve said screen from tension, and means on said bar to engage the sash of the window.

JULIAN J. WOLOSEZYN.
